UNITED STATES PATENT OFFICE.

A. ELY BEACH, OF STRATFORD, CONNECTICUT.

IMPROVED METHOD OF TRANSPORTING LETTERS AND PARCELS.

Specification forming part of Letters Patent No. 96,187, dated October 26, 1869.

To all whom it may concern:

Be it known that I, A. ELY BEACH, of Stratford, in the county of Fairfield and State of Connecticut, have invented new and useful Improvements in the Transportation of Letters, Parcels, and other Freight by Atmospheric Pressure; and I do hereby declare that the following is a full, clear, and exact description thereof, which will enable others skilled in the art to make and use the same, reference being had to the accompanying drawings, forming part of this specification.

The usual atmospheric method of transporting freight is by means of vehicles—such as ears, balls, bags, or hollow pistons—which contain the freight, and fit within a tube, and are therein propelled by the force of an air-current.

The object of the present improvements is to dispense with the use of such vehicles and transport the freight by submitting it to the direct action of the air-currents.

My invention further consists in the employment of certain devices to facilitate the receiving and discharging of the freight, as hereinafter set forth.

Figure 1 is a perspective view, showing the employment of a part of my improvements in connection with a street-lamp post letter-box. Fig. 2 is a sectional end elevation of one of my improved receiving and discharging boxes. Fig. 3 is a sectional side elevation of the same. Fig. 4 is a side elevation of a modified form of a receiving-box. Fig. 5 is a plan view, in part sectional, of my improved shifting air-pipe.

Similar letters of reference indicate corresponding parts.

In carrying out my invention I provide air-tubes A A' A", made of wood, metal, or other materials, of suitable size and strength, having a smooth interior.

In some cases the interiors of the tubes are lined with cloth or rubber or other soft material. By means of a suitable blowing-engine, I drive or draw a current of air through the tubes A A' A" of sufficient force to buoy and carry along all letters, parcels, or other freight that may be deposited within the tubes at any point on the route thereof.

In order to discharge from or deposit the letters, parcels, or other freight within the tubes, I combine therewith, at suitable places, the rotary boxes C. These boxes are composed of wings or partitions a a a a, mounted

on and radiating from a central shaft, b, forming compartments 1 2 3 4, for the reception of letters and parcels. The outer edges of the wings a are intended to move in contact with the casing B, the arrangement and construction of the wings and casing being such that in whatever position the wings may happen to stand two or more of them will always be in contact with the casing B, and thereby prevent the escape of air to or from the pipes A.

Letters, parcels, and freight intended for the air-tubes A are placed within the mouth or hopper B', whence they fall into the uppermost compartment of the rotary letter-box C. The crank b is then turned, and the contents of the compartments fall into the air-tubes A and are at once carried along in the tubes by the air-current, the course of which is indicated by the arrows.

The letter-boxes C may be employed in the several offices and stations of the pneumatic route, as in Figs. 2 and 3, and may also be arranged within suitable pedestals or street-lamp posts, as indicated in Fig. 1.

Various modifications may be made of the letter receiving and discharging devices, all capable of effecting the same necessary result—namely, the deposit and discharge of freight into and from the air-tubes without escape or access of air. One example of such modifications is shown in Fig. 4, in which K is a pipe communicating with the air-tube A. The upper part of pipe K is closed with a cover, f, through which is a slot, g, for the introduction of letters. The slot g is covered to prevent escape of air from tube A by means of the cover L, which is hinged at h to the cover f. An ear, i, projects from the cover L, and a spring-rod, M, extends from ear i, and connects with one end of valve N, which is so pivoted and arranged within the pipe K that when the cover L is closed the valve N will stand open; but when the cover L is raised for the insertion of letters the valve N will cut off the escape of air through slot g by closing against the bottom of the sleeve O, which surrounds slot g, and is fastened to the under side of cover f. When the cover L is again closed, the valve N will open and the deposited letters will fall into the air-tube A.

The above modification may be readily arranged within the street-lamp posts.

At the stations, where the letters, parcels, and other articles are to be discharged from the air-tubes A, the latter are separated, and

A. BEARDSLEY.
